UNITED STATES PATENT OFFICE.

MILO COVEL, OF CHICAGO, ILLINOIS.

SAW-SWAGING MACHINE.

SPECIFICATION forming part of Letters Patent No. 398,032, dated February 19, 1889.

Application filed October 18, 1888. Serial No. 288,456. (No model.)

To all whom it may concern:

Be it known that I, MILO COVEL, of Chicago, county of Cook, and State of Illinois, have invented certain new and useful Improvements in Saw-Swaging Machines, of which the following is a full, clear, and exact description, that will enable others to make and use the same, reference being had to the accompanying drawings, forming a part of this specification.

This invention relates to improvements in that class of devices that are more especially intended for use on band and gang saws; and to this end the same consists of certain novel features in the construction, combination, and arrangement of the several parts, as will be hereinafter set forth.

Figure 1 is a front elevation of a machine embodying my improved features; Fig. 2, a horizontal section in plane 2, Fig. 1, looking in the direction indicated by the arrow; Fig. 3, a vertical transverse section in plane 3, Fig. 1; Fig. 4, a broken-away horizontal section in plane 4, Fig. 3; and Fig. 5, a detached detail of the swaging-dies.

Referring to the drawings, A represents the different parts comprising the supporting-frame; A', the driving-shaft, provided with suitable journal-bearings in the frame; and 30 A² A³, the usual band-pulleys mounted on the outer end of said shaft.

The head-block A⁴ is mounted on the top of the supporting-frame. The horizontal rocking die B is inserted transversely through the head-block. One end of the link B' is rigidly secured to the roller-die and the opposite end pivoted to the upper end of the connecting-rod B², the lower end of which is in turn properly connected to the hub of the eccentric-strap B³, mounted on the cam and crank wheel B⁴, as shown in Figs. 1 and 2. By this means a slight rolling or rocking movement is imparted to the die B. This roller-die is provided with a recess, as indicated by 45 dotted lines in Fig. 5, at a point in line with the path of the saw for adjustably seating the die-point a, which is retained in place by the set-screw a', inserted in the front end of the roller-die, this die-point can be set at any 50 angle desired, and can be readily removed to

be dressed or replaced by another when worn out.

The stationary die C is inserted diagonally through the head-block from the top, as shown in Fig. 1. The position of the same being indicated by dotted lines. The stationary die-bar C has a threaded engagement with the screw-bolt C', whereby the stationary die may be properly set with reference to the rolling die.

The vertical guides C² C³ are bolted to the frame, the cross-head C⁴ having a vertical movement between the same. The step-block a⁵ is bolted to the front side of the cross-head and forms a rest or seat for the back of the saw C⁵ during the swaging process.

a⁶ is a plate bolted to the upwardly-projecting rectangular flange a⁵ of the cross-bar C⁶, as shown in Figs. 1 and 3.

The lower end of the outer vertically-aranged clamping-bar, D, rests upon the flange a⁵, and is adjustably secured to the cross-head C⁴ by hand-screw a⁶. The lower part of the companion clamping-bar D' is rigidly secured to the cross-head. The upper ends of 75 these bars are beveled on their outer sides, as at a⁷.

a⁸ a⁹ are spring clamping-jaws lying in a horizontal plane, the outer ends of which are bolted to the head-block, the inner or opposite ends bearing against the outer sides and upper ends of the bars, as shown in Figs. 3 and 4. The contacting ends of the spring-jaws are correspondingly beveled, so that when the saw-clamping bars and the spring-jaws engage it is with a wedge-like action. This arrangement provides an automatically-operating clamp. On the down movement the pressure on the saw is early relaxed, leaving the same free to be moved by the feed mechanism to bring the next tooth into position to be swaged. On the up movement the saw is firmly clamped just before the teeth come in contact with the swaging-dies. The screws b b are for the purpose of securing a proper adjustment between the clamping-bars and spring-jaws.

The vertical adjusting-screws b' b' are inserted in the under side of the cross-head C⁴, and ordinarily will have the head ends rest 100

on the upwardly-projecting flange a^5 of the cross-bar C^6 . By lengthening or shortening said screws the cross-head may be set higher or lower, in accordance with the width of the

5 saw inserted between the clamping-bars.

The cross-bar C^6 has a vertical movement between the stationary guides C^2 C^3 , and is cut away on the under side at one end to form the beveled shoulder b^2 , (see Fig. 1,) normally 10 engaging with the correspondingly-beveled offset b^3 in the slide-bar E , on which the cross-bar rests. The opposite end and under side of the cross-bar C^6 is provided with the downwardly-projecting part b^1 , having the beveled shoulder b^5 normally engaging with the beveled part b^6 on the upper side of the slide-bar E . One end of the connecting-rod D^2 is pivoted to the extended end of the slide-bar E and the other end properly connected to 15 the crank-wheel B^4 , as shown in Figs. 1 and 2. Now as the crank-wheel rotates a reciprocating and endwise movement is imparted to the slide-bar E , which has, by reason of the beveled contacting-surfaces, the effect of 20 raising and lowering the cross-bar and cross-head and bringing the saw into position at each movement to be operated upon by the swaging-dies.

The vertical screw-shaft F has a threaded 25 engagement with the rear side of the cross-head, (see Fig. 3,) and has the pinion-wheel d mounted on the lower end, which engages in turn with the pinion d' on the inner end of the horizontal shaft F' , journaled in the 30 cross-bar C^6 . The outer end of the shaft F' is square, to receive a suitable handle for rotating the same, thus providing a means for raising and lowering the cross-head when adjusting the saw with relation to the swaging-dies. The spiral spring d^2 serves to assist in 35 the down movement of the cross-head and parts.

F^2 is a bevel-pinion mounted on the inner 40 end of the driving-shaft A' and engages with the gear-wheel F^3 , mounted on the back end of the counter-shaft F^4 , carrying the crank and cam wheel B^4 on the opposite end, as 45 shown in Fig. 2, this arrangement transmitting the required motion and power to raise 50 up and bring the saw in contact with the swaging-dies once in each revolution.

The feed-lever H is bolted to the bell-crank lever H' at d^3 , which is in turn connected to the hub of the eccentric-strap B^3 by the pivotal link d^4 . To the upper end of the lever H is pivoted one end of the feed-finger H^2 , the opposite end engaging with the teeth of the saw, by which means the saw is moved along, bringing the teeth in regular order to the 60 faces of the swaging-dies. The gage-bolt h is inserted through the upward-projecting part of the bell-crank, and has a loose contact with the outer edge of the feed-lever near its longitudinal center. A second gage-bolt, h' , is 65 inserted through the lower end of the feed-lever, and so arranged that the head end will have an intermittent contact with the guide

70 C^2 . The function of these gage-bolts is to regulate the throw of the feed-lever by adjusting or setting them as circumstances may require.

The spring h^2 assists in returning the feed mechanism to its normal position.

It is of course understood that the different parts must be properly adjusted and set 75 so as to time the movement of the same with reference to each other.

Having thus described my invention, what I claim, and desire to secure by Letters Patent, 80 is—

1. In a saw-swage, the combination, with the frame, of the head-block, the rocking or rolling die inserted in said head-block, the link, connected at the inner end to said die, the connecting-rod pivoted to the outer end of 85 said link, the eccentric-strap, in which the lower end of the connecting-rod is inserted, the cam or crank wheel, and the counter-shaft upon which the same is mounted, whereby the required motion is transmitted 90 to the roller-die, substantially as and for the purpose set forth.

2. In a saw-swage, the combination, with the frame, of the head-block supported thereon, the rocking or roller die inserted horizontally in said head-block and provided with a recess in the line of the saw, the adjustable die-point seated in said recess, the stationary die passing diagonally through said head-block, and the screw-bolt having a threaded engagement with the rear end of said stationary die, whereby the same may be adjusted with reference to the roller-die, and the die-point inserted therein, substantially as and for the 95 purpose set forth.

3. In a saw-swage, the combination, with the frame, of the vertical guides bolted thereto, a cross-head moving between said guides and provided with a seat-rest for a saw, the saw-clamping bars secured to and moving 100 with the cross-head, a cross-bar having beveled shoulders on the under side, as described, and arranged between said guides below the cross-head, the plate a^4 , bolted to the cross-bar, the slide-bar E engaging with the under 105 side of the cross-bar and having beveled shoulders, the connecting-rod D^2 , the crank-wheel B^4 , and the counter-shaft upon which 110 the same is mounted, whereby a vertical movement is transmitted to the cross-head and the saw raised to bring the teeth in position to be operated upon by the swaging-dies once in each revolution of the crank-wheel, 115 substantially as set forth.

4. In a saw-swage, the combination, with the head-block, of the saw-clamping bars having beveled upper ends, the spring-jaws rigidly secured at one end, the opposite beveled ends bearing loosely against the outer beveled surfaces of the clamping-bars, and 120 the adjusting-screws inserted through the head-block and having contact with said jaws, 125 substantially as and for the purpose set forth.

5. In a saw-swage, the combination, with 130

the cross-head C⁴ and the cross-bar C⁶, of the adjusting screw-bolts b' b', inserted in the under side of said cross-head and adapted to rest on the upwardly-projecting flange a⁵, forming a part of said cross-bar, substantially as and for the purpose set forth.

6. In a saw-swage, the combination, with the frame, of the cross-head, the cross-bar C⁶, the vertical screw-shaft F, the pinion-wheel d, the horizontal shaft F', and the pinion d', whereby the saw may be raised by hand for the purpose of securing the proper adjustment of the same relative to the swaging-dies, substantially as and for the purpose set forth.
- 15 7. In a saw-swage, the combination of the

feed-lever II, the bell-crank lever II', the eccentric-strap B³, the link d⁴, and the feed-finger H², whereby the saw-teeth are automatically presented to the swaging-dies in regular order of succession, substantially as 20 set forth.

8. In a saw-swage, the combination of the feed-lever, the feed-finger pivoted to the upper end thereof, the bell-crank, and the gage-bolts h h', substantially as and for the purpose set forth. 25
